UNITED STATES PATENT OFFICE.

ARTHUR WATNEY, OF CALAIS, FRANCE.

DESIGN FOR A LACE FABRIC.

SPECIFICATION forming part of Design No. 23,260, dated May 15, 1894.

Application filed April 5, 1894. Serial No. 506,508. Term of patent 3½ years.

To all whom it may concern:

Be it known that I, ARTHUR WATNEY, a citizen of England, and a resident of Calais, France, have invented a new and original Design for Lace Fabrics, of which the following is a specification, reference being had to the accompanying drawing, showing a part thereof. The drawing represents a piece of my newly designed lace fabric.

10 The leading feature of my design consists of leaf-like ornaments having rolled tips and arranged in series, the ornaments of each series being connected by branches.

15 *a, b, represent two series of leaf-like ornaments, provided with rolled tips *a', b'*. The ornaments of each series are provided with*

small flowers *a², b²*, upon their body, and are connected by branches *a³, b³*. The series *a*, is composed of larger ornaments than the series *b*, and is provided with the arched margin *c*, to constitute a border.

What I claim is—

The design for a lace fabric, substantially as shown and described.

In testimony that I claim the foregoing as my invention I have signed my name, in presence of two witnesses, this 20th day of February, 1894.

ARTHUR WATNEY.
